United States Patent Office

Des. 175,340

Patented Aug. 16, 1955

175,340

CHESS PIECE

Donald E. Folley, Fayetteville, N. Y.

Application April 26, 1954, Serial No. 30,172

Term of patent 3½ years

(Cl. D34—5)

FIG. 4

FIG. 3

FIG. 2

FIG. 1

FIG. 6

FIG. 5

Figure 1 is a side elevational view of the right side of a chess piece embodying my new design;

Figure 2 is a front elevational view thereof;

Figure 3 is a side elevational view of the left side thereof;

Figure 4 is a back elevational view thereof;

Figure 5 is a top plan view thereof; and

Figure 6 is a fragmentary vertical section through the piece taken along line 6—6 of Figure 5.

I claim:

The ornamental design for a chess piece, as shown.
